UNITED STATES PATENT OFFICE.

AARON N. WARFIELD, OF LONDON, ONTARIO, CANADA.

CAR CONSTRUCTION.

1,274,113.

Specification of Letters Patent. Patented July 30, 1918.

Application filed June 7, 1917. Serial No. 173,297.

To all whom it may concern:

Be it known that I, AARON N. WARFIELD, a citizen of the United States of America, residing at London, in the county of Middlesex and Province of Ontario, Dominion of Canada, have invented certain new and useful Improvements in Car Construction, of which the following is a specification, reference being had therein to the accompanying drawings.

This invention relates to car construction, and has special reference to certain improvements in connection with the construction disclosed by my Patent No. 1,230,349, granted June 19, 1917, and my application filed Oct. 23, 1916, Serial No. 127,059, and allowed Oct. 18, 1917.

The present invention particularly relates to the underframing of the metallic railway car, either for steam or electric railways, and especially the underframing at the ends of the car, such underframing including the central box girder, transverse end bolsters, bulk heads, and platform extensions.

The official reports of recently wrecked steel passenger coaches attribute the crushing and buckling of the ends of the coaches due to a lack of proper bracing, reinforcements, and disposal of structural elements to resist end thrust or compression, and it was found that while the structural elements were disposed to insure rigidity under normal conditions, that these same elements were susceptible to buckling under minimum end thrust or compression. The same reports found the car construction otherwise faulty and my invention now aims to rectify such faults by a car construction capable of withstanding many times, the end thrust or compression so far encountered in wrecked cars, without increasing the weight of the car. To accomplish this, it has not been necessary to increase the weight or cross sectional area of structural standard shapes, as channels, I beams or angle bars, but to dispose such structural elements and articulate the same so that buckling or distortion from any lateral direction is practically impossible.

The present invention includes many novel features that will be apparent to those conversant with metal car construction, and reference will now be had to the drawings, wherein

Figure 1 is a plan of the underframing of

an end of a car, showing head and side walls in section;

Fig. 2 is an enlarged plan of an end bolster, partly broken away and partly in section;

Fig. 3 is a cross sectional view taken on the line III—III of Fig. 1, showing the end bolster in elevation;

Fig. 4 is a cross sectional view taken on the line IV—IV of Fig. 3;

Fig. 5 is a longitudinal sectional view taken on the line V—V of Fig. 1, showing the central longitudinal box girder in elevation, and

Fig. 6 is a cross sectional view taken on the line VI—VI of Fig. 1, showing a portion of the bulk head.

Reference will first be had to the central longitudinal box girder constituting the backbone of the car, this girder, together with the underframing of the car body, being susceptible to all the impact under abnormal conditions. The girder extends throughout the length of the underframing and consists of I beams 1 connected by top and bottom plates 2 and 3 respectively. These top and bottom plates are only discontinued where much heavier reinforcing or gusset plates are used in lieu thereof, particularly bolsters and transverse beams or members of the underframing. Where bolsters are to straddle the box girder the bottom plate 3 abuts a bottom center plate 5 and is riveted or otherwise connected to the I beams 1 of the girder.

Each bolster comprises transverse webs 6 disposed in parallelism with the lower edges thereof cut away, as at 7, so that the webs may straddle the box girder and be held relative thereto. At the box girder, the outer sides of the webs 6 are connected to the I beams by angle brackets 8, and the confronting walls of the webs are connected to the I beams 1 by angle brackets 9, as best shown in Fig. 2. Angle bars 10 also connect the outer sides of the webs 6 to the top plate 2.

The lower edges of the webs 6, at the inner and outer sides thereof, are provided with angle bars 11, extending from the bottom center plate 5, to the outer ends of the webs 6, and these angle bars are connected by a bottom cover plate 12 extending under the plate 5 and protruding from the ends of the webs 6, as best shown in Fig. 3. The bottom cover plate 12 at the box girder, is rein-

forced by another bottom plate 13, the reinforcing plate 13 cover plate 12, angle bars 11, connecting the lower edges of the webs 6 to the box girder so as to resist crushing 5 of the girder due to loads on the ends of the girder. To prevent breaking of the bolster at that point where it straddles the box girder, the upper edges of the webs 6, at the confronting sides thereof, are provided with 10 channel bars 14 throughout the length thereof and these channel bars, together with angle bars 15 at the outer sides of the webs 6, are connected to top or cover plate 17 having a central reinforcing plate 18. The channel bars 14, angle bars 15, plates 17 and 18 15 coöperate with the angle bars 10 in reinforcing that part of the bolster straddling the box girder, so that said bolster will not be weakened by being cut away, as at 7, to 20 straddle the box girder.

Resting on the protruding ends of the bottom cover plate 12 and connected thereto are web plate side girders forming the subject matter of my Patent No. 1,230,349 here- 25 tofore mentioned. As an instance of such construction, there is a bottom member 19 supporting a wall 20 having the lower edges thereof connected to the member 19 by angle bars 21 and 22. The top cover plate 17 of 30 the bolster abuts the wall 20 and is connected thereto by angle bars 23 and 24. An outside plate 25 stiffens the wall 20 at the end of the bolster, as clearly shown in Figs. 2 and 3. The outer and inner sides of the webs 6 of 35 the bolster are also connected to the angle bar 22 by angle brackets 26.

The side plate girders of the car are connected by transverse channel members 27 and 28 on the central box girder and connected to the transverse member 28 is a bottom bulk head plate 29 provided with an opening 30 to receive the central box girder. The same rivets or fastening means holding the bottom bulk head plate 29 in engagement 40 with the transverse member 28 also holds the lower edges of bulk head plates 31, having the vertical inner edges thereof reinforced by vertical angle bars 32 and the vertical outer edges thereof connected to the 45 side web plate girders by angle bars 33, 34 and 35, the angle bars 33 extending on to the bottom bulk head plate 29, and connected thereto, as best shown in Fig. 6.

Between the bolster and the transverse member 27 and between this member and the transverse member 28 are longitudinally alining channel members 36 connected to the bolster and the members 27 and 28 by angle brackets 37. Riveted or otherwise 50 connected to the upper flanges of the members 27, 28, and 36 is a large impact plate 38, having the side edges thereof connected to the angle bars 24, and the inner transverse edge thereof connected to the angle bar 15 55 of the bolster, this bar having the lateral

flange thereof protruding from under the cover plate 17, as best shown in Figs. 2 and 5. The impact plate 38 provides a lateral solid truss member between the bulk head, bolster and side web plate girders. Further stiffening the end of the underframing are angularly disposed braces 39^a extending through the lower bulk head plate 29 and connecting the side web plate girders to the outer ends of the I beams 1 of the box 75 girder. The protruding ends of the central box girder support transverse platform members 39 and 40, the former being shaped to conform to the end contour of the car body or platform. The transverse platform 80 members 39 and 40 are connected by longitudinal channel members 41 and longitudinal channel members 42 connect the transverse platform member 39 to the bulk head. The longitudinal channel members 42 are 85 connected to the bulk head by angle brackets 43 and riveted or otherwise attached to the upper flanges of the longitudinal channel members 42 and the transverse platform members 39 and 40 is a platform plate 44. 90 This plate, at the bulk head, is attached to transverse angle bars 45 carried by the bulk head. The platform plate 44 is in reality a continuation of the impact plate 38 and the manner of articulating the platform structure relative to the end bolster is such as to distribute stresses and strains and resist the maximum impact to which steel railway cars have so far been subjected. 95

The above is an outline of the principal 100 structural features of the car underframing, and minor angle brackets, braces and gusset plates have not been included. The preferred structural elements have been shown and described, and it is to be understood 105 that the construction and arrangement of such elements are susceptible to such changes as fall within the scope of the appended claims.

What I claim is:—

1. An underframing for cars, comprising a box girder, side web plate girders, a bolster straddling said box girder and connected to said side girders, transverse members on said box girder connecting said side girders, and an impact plate connecting said side plate girders, said transverse members and said bolster. 110
2. An underframing for cars, comprising a box girder, side web plate girders, a bolster straddling said box girder and connected to said side girders, transverse members on said box girder connecting said side girders, a bulk head carried by said box girder and one of said transverse members 115 connected to said side girders, and a horizontal disposed impact plate connecting said side girders, said transverse members and said bolster. 120
3. An underframing for cars, comprising 125

5 a box girder, side web plate girders, a bolster on said box girder and connected to said side girders, transverse members on said box girder connected to said side girders, trans-
10 verse platform members on said box girder, a horizontal impact plate connecting said side girders, said transverse members and said bolster, and horizontal platform plate connecting said transverse platform mem-
bers and in a plane with said impact plate.

15 4. An underframing for cars, comprising a box girder, side web plate girders, a bolster on said box girder and connected to said side girders, transverse members on said box girder connecting said side girders, a bulk head carried by said box girder and one of said transverse members and connected to said side girders, transverse platform mem-
20 bers on said box girder, a horizontal plat- form plate connecting said transverse plat- form members to said bulk head, and an impact plate connecting said side girders, said transverse members and said bolster.

25 5. In car construction, a box girder, a bottom bulk head plate thereon, a transverse member on said box girder connected to said bottom bulk head plate, side bulk head plates connected to said bottom bulk head plate and said transverse member, a platform

30 plate at one side of said bulk head, and an impact plate at the other side of said bulk head.

35 6. In car construction, a box girder, a bottom bulk head plate thereon, a transverse member on said box girder connected to said bottom bulk head plate, side bulk head plates connected to said bottom bulk head plate and said transverse member, a platform plate at one side of said bulk head, transverse plat-
40 form members on said box girders support- ing said platform plate, a bolster, and an im- pact plate connecting said bulk head and said bolster.

45 7. In car construction, a central girder, side girders, and a bolster straddling said central girder and connected to said side girders and comprising webs having inner and outer sides connected to said central girder, top and bottom cover plates for said webs, and reinforcing plates for said cover plates at said central girder.

50 In testimony whereof I affix my signature in the presence of two witnesses.
